Primary Examiner — Daniel Bui(74) *Attorney, Agent, or Firm* — Fletcher Yoder PC(57) **CLAIM**

I claim the ornamental design for a sensor connector, as shown and described.

DESCRIPTION

FIG. 1 is a perspective view of the sensor connector of the present invention with a movable cover in the open position; FIG. 2 is a perspective view of the sensor connector of FIG. 1 with the movable cover in an alternate closed position; FIG. 3 is a top view of the sensor connector of FIG. 2; FIG. 4 is a bottom view of the sensor connector of FIG. 2; FIG. 5 is a right side view of the sensor connector of FIG. 2; FIG. 6 is a left side view of the sensor connector of FIG. 2; FIG. 7 is a front view of the sensor connector of FIG. 2; and, FIG. 8 is a rear view of the sensor connector of FIG. 2. Any subject matter shown in broken lines in the drawings constitutes the environment only and forms no part of the protection sought.
